CLAIM

The ornamental design for a hinged split wire clamp, as shown and described.

DESCRIPTION

FIGS. 1 and 2 are perspective views of a hinged split wire clamp, showing my new design shown in a closed and hinged open attitude respectively;

FIG. 3 is a right side elevation view thereof, the left side

elevation view being a mirror image thereof;

FIG. 4 is a rear elevational view thereof;

FIG. 5 is a front elevational view thereof;

FIG. 6 is a top plan view thereof; and,

FIG. 7 is a bottom plan view thereof.
